Inventor:

Peter Behr

Issue Aug 27/67

United States Patent Office.

PETER BEHR, OF SAINT LOUIS, MISSOURI.

Design No. 2,775, dated September 10, 1867.

DESIGN FOR A TRADE-MARK.

The Schedule referred to in these Letters Patent and making part of the same.

TO ALL WHOM IT MAY CONCERN:

Be it known that I, PETER BEHR, of the city and county of Saint Louis, State of Missouri, have originated and produced a new Design for a Trade-Mark, of which the following is a full, clear, and exact description, reference being had to the annexed drawing, making a part of this specification.

My design consists of a six-pointed star, with an illuminated hexagonal centre, in combination with the letters "G. B. & Co.," and the words "Saint Louis" in the points of the star, and the words "patented," "trademark" in the centre, together with the date of the patent, if granted, all arranged substantially as shown. The letters "G. B. & Co." will be illuminated.

This is intended to be used as an engraving or brand, and when used as the latter the stencil impression will have such breaks in it as may be necessary to give the requisite strength to the plate by which the impression is made.

What I claim as my invention, and desire to secure by Letters Patent, is—

The design for a trade-mark, substantially as shown and described.

PETER BEHR.
